UNITED STATES PATENT OFFICE.

VICTORIA LENDRESSE, OF NEW ORLEANS, LOUISIANA.

BRASSIÈRE AND DIAPHRAGM SUPPORTER.

Application filed April 3, 1923. Serial No. 629,617.

To all whom it may concern:

Be it known that VICTORIA LENDRESSE, a citizen of the United States, residing at New Orleans, in the parish of Orleans and State 5 of Louisiana, has invented certain new and useful Improvements in Brassières and Diaphragm Supporters, of which the following is a specification.

This invention relates to a brassière and 10 a diaphragm supporter and has for its principal object to provide a brassière that will not only act to support the bust but will also support and reduce the diaphragm.

Another important object of the invention 15 is to provide a brassière and diaphragm supporter of the above mentioned character, which is of such a construction as to enable the same to be worn with comfort and ease to the wearer and is particularly adapted 20 for use with low corsets or girdles.

A still further object of the invention is to provide a brassière and diaphragm supporter of the above mentioned character, which is of such a construction as to insure 25 the proper reinforcing of the same and to securely hold the suspension straps in proper place thereon.

Another important object of the invention 30 is to provide a brassière and diaphragm supporter of the above mentioned character which is simple in construction, inexpensive, strong, durable and well adapted for the purpose for which it is designated.

Other objects and advantages of this invention will become apparent during the 35 course of the following description.

In the accompanying drawings forming a part of this specification and in which like numerals designate like parts throughout 40 the same:

Figure 1 is a view showing the inside of the brassière and diaphragm supporter made in accordance with my invention.

Figure 2 is an outside view thereof.

Figure 3 is a perspective view of the brassière and supporter as shown in Figs. 1 and 2 in position upon the wearer.

Figure 4 is a vertical transverse section taken on line 4—4 of Fig. 3 showing the 50 reinforcing straps in their secured position on the brassière and diaphragm supporter.

In the drawings wherein for the purpose of illustration is shown the preferred embodiment of my invention, the numeral 1 55 designates in the present instance, the front portion of the said brassière and diaphragm

supporter and the central portion thereof tapers towards its ends to provide a comparatively low back portion when applied as shown in Fig. 3 of the drawings. The 60 lower edge of the portion 1 is compoundly curved, as clearly shown in Figs. 1 and 2 of the drawings, while the upper edge is arcuately formed, this design providing the tapering ends as above mentioned. The ends 65 2 and 3 respectively of the brassière and diaphragm supporter are provided with the usual fastening means such as hooks and eyes thereon in the well known manner for the purpose of securing the ends of the brassière when applied in position on the wearer.

The diaphragm supporter which is embodied in my invention consists of an elastic band 4 which is adapted to be secured at its respective ends to the inner face of the 75 lower portion of the said body portion 1 and adjacent the lower edge, in such a manner as to extend the full length of the brassière and is also of a shorter length than the length of the longitudinal length of the 80 brassière so as to provide the elasticity in order to enable the same to properly function.

When in position on the wearer the brassière will be so arranged as to provide the 85 diaphragm supporter in a stretched condition whereby the elastic band extends around the body of the wearer above the waistline and below the bust so as to support the diaphragm.

Secured to the inner face of the brassière and diaphragm supporter are a pair of vertically extending reinforcing strips 6 and 7 which are centrally arranged as shown in Figs. 1 and 2 of the drawings and extend 95 from the lower edge of the diaphragm supporter to the upper edge of the brassière and the reinforcing strips are secured or fastened to the inner face of the brassière by suitable stitchings.

A similar pair of vertically extending supporting strips 8 and 9 are also stitched to the inner face of the brassière and are arranged adjacent the ends 2 and 3 thereof and extend from the upper edge of the 105 brassière to a point a short distance from the lower edge of the diaphragm supporter as more clearly shown in Fig. 2 of the drawings.

Arcuate-shaped reinforcing strips 10 and 110 11 are also stitched to the inner face of the brassière in such a manner as to have one

end thereof stitched to the ends 2 and 3 respectively of the brassière and extend across the brassière and upwardly thereon in such a manner as to join the upper and lower 5 ends of the reinforcing strips in pairs as more clearly shown in Fig. 2 of the drawings. These arcuate reinforcing strips 10 and 11 are stitched to the lower ends of the vertical reinforcing strips 8 and 9 and the 10 upper ends of the arcuate shaped reinforcing strips 10 and 11 merge with the upper ends of the central vertical reinforcing strips 6 and 7 respectively. The elastic band which is stitched at its respective ends 15 to the inner face of the lower portion of the brassière so as to provide suitable means for supporting the diaphragm is also stitched to the central vertical extending reinforcing strips 6 and 7 respectively.

20 These reinforcing strips which are stitched to the inner face of the brassière act as a suitable bracing means and reinforcing means for the brassière and diaphragm supporter whereby the brassière 25 may be supported in the proper position and thereby obviate the necessity of employing suitable reinforcing means such as whalebone which is now commonly used in connection with reinforcing brassières.

30 Furthermore the reinforcing strips which are stitched to the inner face of the brassière are of sufficient construction and arrangement upon the brassière so as to properly support and maintain the brassière in 35 its proper condition and furthermore will lend grace to the figure when worn without inconvenience to the wearer and can be also so arranged upon the brassière to provide an ornamental design of any suitable con- 40 figuration.

Suitable suspension straps 12 and 13 are secured to the upper edges of the brassière in such a manner as to have the respective ends of the suspension straps stitched or secured to the upper ends of the vertical arranged reinforcing strips heretofore described.

It is to be further understood that these reinforcing strips which extend vertically upon the inner face of the brassière may be so secured thereon as to have the suspension straps formed as continuations of the central vertical arranged reinforcing strips and provided with a loop whereby the same may 55 be placed in position upon the wearer and then secured or stitched to the inner face of the brassière at a point adjacent the respective ends thereof. In this manner the suspension straps will not be caused to become 60 loosened or broken from the brassière as is customary with the suspension straps now in use upon the brassières and furthermore will tend to provide additional reinforcing means throughout the entire brassière.

65 Furthermore the strain and pull upon the

suspension straps will be evenly distributed throughout all of the brassière and more preferably over the several vertical reinforcing strips as well as the arcuate shaped reinforcing strips.

The reinforcing strips both vertically arranged and arcuate shaped may be formed of any suitable material and when the brassière is worn as shown in Fig. 3 of the drawings the front face of the brassière will provide a neat and ornamental design and will not show any of the reinforcing strips or the elastic band for supporting the diaphragm.

The simplicity and efficiency of the brassière as above described renders the same very efficient and useful and furthermore can be obtained at a minimum cost.

From the foregoing description of the construction of my improved apparatus, it will be seen that I have provided a simple, inexpensive and efficient means for carrying out the objects of the invention, and while I have particularly described the elements best adapted to perform the functions set forth, it is obvious that various changes in form, proportion and in the minor details of construction may be resorted to, without departing from the spirit or sacrificing any of the principles of the invention.

What I claim as new and desire to secure by Letters Patent is:—

1. A combined brassière and diaphragm supporter of the above mentioned character comprising a body encircling member, said body encircling member tapering smaller towards its ends to provide a comparatively low back portion, means for securing the ends together, an elastic band secured to the inner face of the said member adjacent the lower edge thereof and extending the full length thereof to aid in supporting the diaphragm, vertical and arcuate reinforcing strips secured to the said member, and suspension straps at the upper edges of the said member.

2. A combined brassière and diaphragm supporter comprising a body encircling member, said body encircling member tapering smaller towards its ends to provide a comparatively low back portion, means for securing the ends together, an elastic band secured to the inner face of the said member adjacent the lower edge thereof to aid in supporting the diaphragm and extending the full length thereof, vertical and arcuate reinforcing strips secured to the said member at predetermined portions thereon and suspension straps secured to the upper edges of the said vertical reinforcing strips.

3. A combined brassière and diaphragm supporter comprising a body encircling member tapering smaller towards its ends, means for securing the ends together, an elastic band of shorter length than the length

- of the said member; secured to the inner face of the said member adjacent the lower edge thereof to aid in supporting the diaphragm, vertical reinforcing strips secured to the said member, arcuate reinforcing strips secured to the said member and joining the upper and lower ends of the said vertical strips in pairs, and suspension straps secured to the said vertical reinforcing strips at the upper ends thereof.
4. A combined brassière and diaphragm supporter comprising a body member tapering smaller towards its ends, means for securing the ends together, an elastic band of less length than the length of the said member, said elastic band secured to the inner face of the said member adjacent the lower end thereof to aid in supporting the diaphragm, suspension straps having their suspension ends secured to the inner face of the said member and extending across the full width thereof to provide reinforcing strips, and arcuate reinforcing strips for the bust and diaphragm portions of the member connected to the inner face of said member and
5. The said member; secured to the inner face of the said member adjacent the lower edge thereof to aid in supporting the diaphragm, vertical reinforcing strips secured to the said member, arcuate reinforcing strips secured to the said member and joining the upper and lower ends of the said vertical strips in pairs, and suspension straps secured to the said vertical reinforcing strips at the upper ends thereof.
4. A combined brassière and diaphragm supporter comprising a body member having an arcuately formed upper edge and a compoundly curved lower edge, a wide elastic band secured to the inner face of said member adjacent the lower edge thereof, said elastic band being normally of shorter length than said member and stretched to extend the full length of said member, whereby to aid in supporting the diaphragm when the member is applied to the body, straps looped to form suspension means for said member and having portions thereof secured vertically across said body member to form stays, certain of said stays being positioned to form additional bust supporting means and intersecting at their lower portions the aforesaid elastic band to further reinforce the member, and additional reinforcing means for said member.

In testimony whereof I affix my signature.

VICTORIA LENDRESSE.
